(57) **CLAIM**

The ornamental design for a hand-pulled riding toy, as shown and described.

DESCRIPTION

FIG. 1 is a perspective view of one embodiment of the hand-pulled riding toy showing my new design;
FIG. 2 is another perspective view thereof;
FIG. 3 is a front elevation view thereof;
FIG. 4 is a back elevation view thereof;
FIG. 5 is a left elevation view thereof;
FIG. 6 is a right elevation view thereof;
FIG. 7 is an upward plan view thereof; and,
FIG. 8 is a downward plan view thereof.

The broken lines represent portions of the article that form no part of the claim.
